GUIDE APPARATUS OF STEAM TURBINES

Filed Sept. 18, 1924

*Inventor
F. Nobbs
By Marshall Clark*

UNITED STATES PATENT OFFICE.

FRITZ NOBS, OF ENNETBADEN, SWITZERLAND, ASSIGNOR TO AKTIENGESELLSCHAFT BROWN, BOVERI AND CIE., OF BADEN, SWITZERLAND.

GUIDE APPARATUS OF STEAM TURBINES.

Application filed September 18, 1924. Serial No. 738,486.

To all whom it may concern:

Be it known that I, FRITZ NOBS, a Swiss citizen, residing at Ennetbaden, Switzerland, have invented certain new and useful

5 Improvements in the Guide Apparatus of Steam Turbines, of which the following is a specification.

It has already been proposed to construct the guide apparatus of the dia-
10 phragms in steam turbines by casting guide plates in these diaphragms or by bolting complete sections of guide blades upon the said diaphragms. It has already been pro-
posed to construct the blading of the dia-
15 phragms in the same way as is done in the case of the rotors. It has been furthermore proposed to constitute one boundary wall of the guide passages by the actual diaphragm, and to constitute the other boundary wall by
20 means of a separate guide ring portion. In such a construction the guide blades are carried either by the diaphragm or by the said guide ring portion.

The present invention has for its object
25 to provide improvements in the last men-
tioned system of construction and fastening of the guide apparatus of the diaphragms, which shall allow of an accurate and cheap manufacture, and is designed chiefly for use
30 in turbines of small rotor diameters or of high pressure-stages, where small lengths of the blades are predominant.

The present invention consists broadly in
35 the insertion of a guide ring portion as aforesaid into a corresponding annular groove in the diaphragm, said guide ring portion being formed with a conical bearing surface on the side next the casing, so that, in addition to its attachment by means
40 of the special fastening bolts, the said guide ring portion is also pressed steam-tight by the steam pressure acting upon the dia-
phragm, in the same manner as is already known in the case of covering rings mounted
45 on the outer periphery of diaphragms hav-
ing guide passages opening outwards.

In the accompanying drawings:—

Figs. 1 and 2 illustrate a constructional example of an improved guide apparatus of
50 this invention, in two sections taken at right angles to each other through the respective part of the turbine.

Figure 3 is a section of the diaphragm alone.

Figures 3^a, 3^b and 3^c show the ring portion 55 with integral blades milled therefrom with blades cast therein and with blades inset therein respectively.

Figure 4 and 5 are sections of the dia-
phragms with blades milled therefrom and 60 with blades cast therein respectively and

Figures 4^a and 5^a represent the ring por-
tion in section for Figures 4 and 5 respec-
tively.

In these figures: *a* is a diaphragm; *b* is a 65 guide ring portion bearing with a conical surface *c* upon the casing *d*; and *e* is a rotor. The steam pressure upon the diaphragm is taken by strong ribs *f*. The conical shape of the bearing surface *c* not only effects an axial 70 jointing of the surface *g*, but also acts to press the ends of the blades radially against the inner boundary surface *h*.

The blades *k* of the guide apparatus may 75 be formed by milling out of the solid ring portion or by any other suitable known means. As the passages are open inwards, it is possible to achieve accuracy of manufac-
ture, a good design of the proportions of the 80 cross sections and the angles, and to obtain smooth surfaces.

This improved manner of fastening may of course, be employed for the first group of nozzles of a turbine.

Instead of mounting the guide blades *k* on the ring portions *b*, they may be fastened directly to the diaphragm *a*. In such a case the blade-less ring portion *b* would serve as a covering ring for the blade passages, and, as before, act to the joint the jointing surface *g* as well as the outer boundary surface *l* of the guide apparatus.

What I claim is:—

1. A guide apparatus for the diaphragms 95 of steam turbines having ring portions which are made separate from the dia-
phragms and which constitute one bound-
ary wall of the guide passages, the other bound-
ary wall being constituted by the re-
spective diaphragm, characterized by the 100 feature that the ring portion is provided with a conical surface bearing upon a cor-
responding conical surface on the turbine casing, a cylindrical surface bearing upon a corresponding surface on the diaphragm and an annular surface, substantially at right angles to the axis of the turbine, bearing upon a corresponding complete annular sur- 105

face on the diaphragm, the diaphragm, ring portion and the casing being so arranged that steam pressure on the diaphragm causes the ring portion to be pressed against the 5 conical surface of the casing and thus also against the cylindrical surface on the dia- phragm.

2. A guide apparatus as claimed in claim 1, characterized by the feature that the blades are milled out of the ring portion. 10

In testimony whereof I have signed my name to this specification.

FRITZ NOBS.
